UNITED STATES PATENT OFFICE.

ARTHUR SCHWARZ, OF BERLIN-SCHÖNEBERG, GERMANY.

APPARATUS FOR TONING PHOTOGRAPHS.

SPECIFICATION forming part of Letters Patent No. 708,671, dated July 1, 1902.

Application filed May 10, 1897. Serial No. 635,864. (No model.)

To all whom it may concern:

Be it known that I, ARTHUR SCHWARZ, a subject of the German Emperor, residing at Berlin-Schöneberg, Germany, have invented 5 certain new and useful Improvements in Apparatus for Toning Photographs, of which the following is a specification.

In the manufacture of photographs the sensitized paper is fed through the several baths 10 for developing, toning, and fixing the pictures. With this operation as hitherto carried out only one and the same toning of the photographs is obtained, because the strip of paper is continually fed at a uniform speed 15 through the several baths. I have devised a new apparatus whereby the treatment of the strip of sensitized and exposed paper is also carried out in a continuous manner, but which is so constructed that it enables me to obtain 20 different shades in the toning of the photographs. I have attained this purpose by devising arrangements enabling me to shorten or extend at will the period during which the photographs are treated in the baths, either 25 by increasing or decreasing the speed of feeding of the paper through the baths or by immersing the loops of paper more or less deep into the baths, whereby the speed of the travel of the paper remains unchanged.

30 I have illustrated my new apparatus in the annexed drawings, making a part of this specification, same letters of reference being used for the same parts in the several views, and wherein—

35 Figure 1 shows an apparatus wherein the toning of the photographs can be regulated by changing the speed of travel of the paper through the baths and also embodying a device enabling me to prevent the loss of a part 40 of the paper when same should tear in the course of the process. Fig. 2 shows a plan view, on a larger scale, of the mechanism for changing the speed of travel of the paper. Fig. 3 shows a sectional front view of a bath 45 embodying a device to change the depth of immersion of the paper. Fig. 4 shows a sectional side view of the same bath, the paper being immersed very deep. Fig. 5 shows a similar view with a very shallow immersion 50 of the paper. Figs. 6 and 7 show details of construction. Fig. 8 shows a sectional front view of a bath equipped with a modified con-

struction of the device for regulating the depth of the immersion of the paper.

The exposed paper P is, as usual, wound 55 upon the reel R and is fed over the feeding-rolls W W' W², &c., through the baths I, II, III, and IV, the loops of paper being weighted down in each bath by means of the small rolls r. The feeding-rolls W W' W², &c., are 60 rotated at uniform speed by the shaft L by means of worm-gears N. At its end the shaft L carries a disk a in frictional contact with a friction-roller b, rigidly mounted upon the shaft B, so that the shaft L is rotated by the 65 shaft B. This shaft B is adapted to be moved in an axial direction by means of the hand-wheel C, Fig. 2, so as to shift the point of contact of the friction-roller b and the disk a. It is obvious that the farther the roller b is 70 removed from the center of disk a the slower the rotation of the shaft L will be, and vice versa. These changes in speed may of course be effected gradually by means of the mechanism described, and by these means I am 75 enabled perfectly to regulate the speed of the travel of the paper through the baths.

The shaft B is rotated by a belt d, laid over the stepped pulleys D D' D², as shown in Fig. 2, and this arrangement affords another means 80 roughly to regulate the time of treatment of the paper; but as each rate of speed as obtained by the shifting of the belt d can be further minutely changed by means of the shifting of the point of contact between roller 85 b and disk a the mechanism described affords the means exactly to regulate the speed of the travel of the paper.

If it should be desired not to change the speed of travel of the paper or, if besides this, 90 it should be preferred to use another means for changing the toning of the photographs, I make use of the arrangement illustrated in Figs. 3 to 7. To this end the opposite walls of the receptacles are provided with rails that 95 are extended parallel up to the ceiling of the work-room. These rails should be formed so as to prevent a lateral motion of the rollers e', running thereon, and should be preferably of the form shown in cross-section in Fig. 6. 100 A frame E, preferably of the form shown in Fig. 3 and provided at its four corners with rollers e', corresponding in shape to the rails e, is adapted to be moved vertically up and

down between said rails. This operation is conveniently performed by means of a counterweight Q . The frame E is provided at its lower end with a guide-roll r , adapted to 5 guide the paper in the bath. As shown in Fig. 6, the pivots r' of the roll r are housed in slots r^2 in the downward-extending projections r^1 of the frame E and are kept in place by pins r^3 . A clamping device F , the 10 cheeks $f' f^2$, Fig. 7, of which clasp the rail e and are clamped together by the screw f^3 , prevents any unintentional motion of the frame E . The clamping device F is hinged to the frame E and is moved back in the position shown in dotted lines in Fig. 3 if the 15 frame is to be taken out of the rails. The frame and the rails are made of metal, hard rubber, or any other suitable material which is not affected by the baths. The time during 20 which the paper is submitted to the action of the bath if it travels at uniform speed depends upon the length of the travel through the bath. With the device just described the length of this travel can be varied at will by shifting the position of the frame. Fig. 4 shows the frame lowered into the bath, and Fig. 5 shows it in a raised position. In this way any desired shade of toning can be obtained, and if the position of 25 the frame for a certain tone is once ascertained all pictures will be uniformly toned.

The arrangement described embodies a superstructure which in some cases may be undesirable and which is done away with in the 30 modification illustrated in Fig. 8.

The loop of paper depends into the baths from the feeding-roll W and is weighted down by the guide-roll r . The axle of roll r is housed in slide-pieces r^5 , that slide on the rail 40 e when the roll r is displaced. Close to the slide-pieces r^5 , which may of course be substituted by small rollers, are attached cords s and s' by means of a loop or a ring, as shown, so that when the two cords s and s' are pulled 45 down at the same time and with the same force the roll r is lowered parallel to the travel of the paper. The downward motion of the roll r in this construction is effected by the weight Q' acting upon the cords s and s' , 50 while the upward motion of the roll r is effected by the upward pull of the strip of paper traveling through the bath. For this purpose the cord s is passed over the bottom roll x and then passes upward over the roll X 55 and is then passed between the clamping-rollers $y' y^2$ to the weight. The cord s' first passes around roll x' , thence to roll x , and thence parallel to cord s to the weight Q' . If the weight Q' and the weight of the guide- 60 roll r are sufficient to overcome the upward pull of the strip of paper moved by the feeding-roll W , the weight Q' and the cords s s' will pull the guide-roll r downward as soon as 65 these cords be released. As in this case the pull at both ends of the guide-roll r is entirely the same, said roll r will be lowered and remain parallel to the axle of the feeding-roll W .

In order to secure the guide-roll r at any desired height, the cords s s' are passed between clamping-rollers $y' y^2$, the roller y' 70 having a fixed axle, while the axle of roller y^2 is movable in the oblique slot z . If the roll y^2 is pulled upward, so that its axle becomes located in the upper part of the slot z , the clamping action on the cords s s' is released, the weight Q' moves downward and 75 pulls the guide-roll r , and consequently the loop of paper, deeper into the bath. If the roller y^2 is then released, it will pull back by its own weight the cords s s' , and owing to 80 its oblique slot it clamps the cords immediately against roller y' , so that the desired adjustment is obtained. If, on the contrary, the paper is desired to become further immersed, it is only necessary to lift the weight 85 Q' , and the roll r will then be raised by the pull of the paper, and as the cords will thereby move in the reversed direction the clamping-rollers $y' y^2$ are automatically opened. 90 As soon as the desired position is reached 95 the weight Q' is again released and under the influence of its weight the clamping action of the rollers $y' y^2$ is at once restored. It is obvious that the movement of the guide-roll r may be obtained by other means; but these are merely modifications, the object in view being to adjust the roll r by a downward pull.

In all the arrangements thus far described it is quite possible that the moist paper may tear in the course of its travel through the baths. 100 If the paper tears, which notwithstanding all possible precautions is apt to occur from time to time as it becomes thoroughly moistened by the solutions, the operation must be interrupted in order to fasten together the two ends. 105 During this time the travel of the paper is interrupted, so that the loop of paper in the toning solution remains subjected to the action, which in most cases is too long, so that this length of paper is spoiled. This more or less 110 frequent loss may be avoided by providing the driving-shaft for the feeding-rolls with a device enabling me to withdraw the lengths of paper located in the toning and developing baths whenever the continuous operation of 115 the apparatus should be interrupted in consequence of a break of the endless band of paper. This arrangement is illustrated in Fig. 1. At any suitable place, preferably behind bath II, which contains the toning solution, the 120 shaft L is cut and the two ends are connected by an easily-operating coupling or clutch o . The right-hand end of the shaft L is, moreover, provided with a crank S . Now if the band of paper becomes torn—for instance, after 125 passing through bath II—the belt d is shifted to the idle pulley and the coupling o is thrown out of gear by means of the lever o' or by any othersuitable device. The right-hand side end of the shaft L is now turned by means of the 130 crank S with equal speed in the opposite direction, and the end of the strip of paper is taken hold of. It is obvious that in this way the paper in the baths I and II will be with-

drawn from same with the same speed as if the continuous operation had not been interrupted. Consequently this length of paper, which would otherwise have been lost, is now 5 saved.

Having now described my invention, what I claim as new, and desire to secure by Letters Patent, is—

1. In an apparatus for developing, toning and fixing a long band of photographic paper, the combination of a bath containing the necessary solution, means for moving the long band of paper through the bath, means for regulating the time of treatment of the paper 10 in the bath to obtain the desired shade of toning, and means for reversing the direction of travel of a part of the paper through the bath in the event of the band of paper becoming severed in its travel through the bath, substantially as described.

2. In an apparatus for developing, toning and fixing a long band of photographic paper, the combination of a series of baths containing the necessary solutions, means for moving 15 the paper through the series of baths at a uniform speed, means for varying the period of time for movement of the paper through the baths, and means for reversing the direction of travel of a part of the paper through 20 the bath in the event of the band of paper becoming severed in its travel through the bath, substantially as described.

3. In an apparatus for developing, toning and fixing a long band of photographic paper, the combination of a series of tanks, feed-rolls 25 arranged to conduct the paper from one tank to another, a shaft common to all the rolls for driving the same and carrying a disk, a shiftable rotatable roll in frictional contact with 30 said disk for varying the speed of the shaft by changing the point of contact between the disk and roll, and means for reversing the direction of travel of a part of the paper through

the bath in the event of the band of paper becoming severed in its travel through the bath, 45 substantially as and for the purposes described.

4. In an apparatus for developing, toning and fixing a long band of photographic paper, the combination of a series of tanks, feed-rolls 50 arranged to conduct the paper from one tank to another, a divided shaft for driving said rolls having its members connected together by a clutching device adapted to disconnect the members to permit one member to rotate 55 independent of the other member, and means for independently operating the disconnected members for withdrawing the band of paper in the event of the same breaking apart, substantially as and for the purposes described. 60

5. In an apparatus for developing, toning and fixing a long band of photographic paper, the combination of a series of tanks, feed-rolls arranged to conduct the paper from one tank to another, a divided shaft for driving said 65 rolls common to all of said rolls and having its members connected together by a clutching device adapted to disconnect the members in the event of accident to permit one member to rotate independently of the other 70 member, means for independently operating the disconnected members for withdrawing the band of paper in the event of the same breaking apart, a disk carried by one of said shaft members, and a shiftable rotatable roll 75 in frictional contact with said disk for varying the speed of the feed-rolls through the shaft common to them all when the members of said shaft are connected, substantially as described. 80

In witness whereof I have hereunto set my hand in presence of two witnesses.

ARTHUR SCHWARZ.
